UNITED STATES PATENT OFFICE.

WILLIAM J. MARTIN, OF BUFFALO, NEW YORK, ASSIGNOR OF ONE-HALF TO FRANCIS J. CARR,
OF BUFFALO, NEW YORK.

AIR-CONTROLLED LOCK FOR SLIDING DOORS.

No. 913,834.

Specification of Letters Patent.

Patented March 2, 1909.

Application filed July 17, 1908. Serial No. 444,038.

To all whom it may concern:

Be it known that I, WILLIAM J. MARTIN, a citizen of the United States, residing at Buffalo, in the county of Erie and State of New York, have invented certain new and useful Improvements in Air-Controlled Locks for Sliding Doors, of which the following is a specification.

My invention relates to air-controlled locks for sliding-doors, and it has for its objects the production of a simple and effective means whereby a door, upon being closed, will become locked automatically and cannot be opened, except by the use of compressed-air, steam, or other power-agent; to so construct the device that it will be wholly confined within the door-jamb; to construct the door-jamb of metal in one integral piece so that it will confine the working parts in a secure manner; and to otherwise improve on locking-devices for sliding-doors.

My invention consists in the construction, arrangement and combination of parts to be hereinafter described and particularly pointed out in the appended claims.

In the drawings,—Figure 1 is a side elevation of a portion of a box-car equipped with my invention. Fig. 2 is an enlarged horizontal section taken on line 2—2, Fig. 4. Fig. 3 is an enlarged horizontal section taken on line 3—3, Fig. 4. Figs. 4 and 5 are vertical sections on a reduced scale, taken on line 4—5, Fig. 2; the parts being shown in different positions. Fig. 6 is a perspective view of a portion of the sliding-door. Fig. 7 is a perspective view of the locking-plunger. Fig. 8 is an enlarged horizontal section taken on line 8—8, Fig. 4. Fig. 9 is an enlarged horizontal section taken on line 9—9, Fig. 4.

Referring now to the drawings in detail, like letters of reference refer to like parts in the several figures.

The reference letter A designates a car, B the door-opening of the car and C the sliding-door which is guided for movement on a rail c in the usual manner.

I have shown this invention applied to a car, for which use it was primarily designed, but its utility is not confined to such purpose, as it may be employed for locking doors of jails, warehouses, residences, and other places where security against intrusion or theft is desired.

Secured to that side of the door-opening against which the door is to close, I secure a

cylinder or cylindrical casting D having securing flanges d through which and the wall of the car, bolts E are passed to secure the casting to the car-wall. Said bolts have countersunk heads and are passed through 60 said parts from the outside and they have nuts e threaded onto their inner ends so that they cannot be removed from outside the car; thus guarding against the removal of said casting. This casting serves as the 65 door-jamb and has two flanges F integral therewith and separated by an intervening door-receiving space f into which the adjacent marginal-portion of the door is to be moved, said space communicating through 70 the greater portion of its length, with the interior of said cylinder.

The cylinder D is closed at its lower end and has a central valve-chamber G surrounded by an annular air-chamber H into 75 which air under pressure is delivered through an inlet-pipe h. Said annular chamber has also an outlet-pipe h' for the escape of air from the cylinder; said outlet-pipe having a valve h''. In the wall separating the valve- 80 chamber from said air-chamber an inlet-port g and an outlet-port g' are provided. Within said chamber a reciprocating cylindrical valve I is located which normally closes the outlet-port g' and leaves the inlet-port g uncovered so that the air may enter the valve 85 casing and so that it cannot escape until the outlet-port is opened. To accomplish this, the ports g and g' are arranged out of line so that when one port is open the other is 90 closed.

At the lower end of said valve, a transverse-arm i is formed integrally therewith in which is secured the lower end of a stem i'' extending centrally up into the cylinder and having its upper end suitably secured 95 to a locking-plunger J vertically movable in the upper end of the cylinder. Said locking-plunger may be of any construction which would properly guide it within the cylinder, but I preferably construct the same with two 100 heads j connected by four vertical webs j' radiating from the center and having in cross-section the form of a cross. By means of this construction, a very light yet strong and rigid plunger is obtained which will withstand all jars and strains to which it may be subjected. The upper end of the casting or cylinder is closed by a plug K between which 105 and the upper end of said plunger, a powerful coil-spring L is interposed.

One of the webs of the plunger has hook lock-arms M projecting therefrom which enter the space between the flanges F and it also has a series of teeth N on said web between said lock-arms. Secured to the sliding-doors are hook lock-arms O which are normally engaged by the lock-arms M of the plunger, the lock-arms on the door and the lock arms on said plunger being oppositely disposed so that they interlock.

Normally resting on the upper wall of the air-chamber H is a piston P having an axial tube R secured thereto which is guided in a cross-bar S in the cylinder and surrounding said tube with one end bearing against said cross-bar, and its other end bearing against the piston is a coil-spring T. The stem i^2 of the valve I extends up through the tube of the piston, for a purpose to be described hereinafter.

Pivottally secured between the flanges F of the cylinder is a weighted detent-pawl U which is adapted for coaction with the series of teeth N, and when the door is closed, said pawl is engaged by a trip-arm V to cause disengagement of said pawl from said teeth and retain the same in disengaged position until the door is being opened, at which time the trip-arm moves away from said detent-pawl and allows the same to gravitate and swing into engagement with one of the series of teeth.

The normal position of the parts is shown in Fig. 4 with the door closed and the lock-arms of the locking-plunger interlocked with the lock-arms on the door, thus securely locking said door. In order to open the door, compressed-air is introduced into the annular air-chamber H, passing from said chamber into the valve-chamber G. The air within the valve-chamber acts against the piston P, causing it to rise and the tube R thereof to strike the lower end of the plunger, which latter is thereby elevated against the action of the spring L and causes the lock-arms M of the plunger to be disengaged from the lock-arms O on the door, thus allowing the latter to be opened. The plunger is held elevated by the detent-pawl U which swings into locking engagement with one of the series of teeth N on the plunger when the trip-arm V on the door is moved away from it.

When the plunger is being elevated, it carries the valve I with it and the latter cuts off the admission of air to the cylinder. When the plunger is elevated to its full extent, the outlet-port g^1 is uncovered and allows the escape of air from the cylinder, provided the valve in the outlet-pipe h^1 is opened, which may be done after the door is drawn away from the plunger and the detent-pawl has engaged the teeth of said plunger. The plunger remains elevated until the air has escaped from the cylinder and the door closed to cause the detent-pawl

to be released from the teeth of the plunger, after which the latter is forced downward into normal position by gravity and by the action of the coil-spring L.

Having thus described my invention, what I claim is,—

1. In a locking-device for doors, the combination with a structure having a door-opening and a door for closing said opening, of a single cylinder serving as a door-jamb, 75 a plunger within said cylinder provided with a locking-element adapted to engage said door, and a valve also in said cylinder governing the admission of the power-agent thereto and the escape of the power-agent 80 therefrom.

2. In a locking-device for doors, the combination with a structure having a door-opening and a door for closing said opening, of a cylinder having a door-receiving groove 85 in communication with its interior, a plunger in said cylinder having a locking-element extending into said door-receiving groove and normally in locking engagement with said door, air-controlled means for actuating said 90 plunger to cause the locking-element thereof to be disengaged from said door, and means to return said plunger to normal position.

3. A locking-device for doors comprising a cylinder closed at its ends, a locking 95 plunger vertically movable within said cylinder, a power-actuated piston within said cylinder beneath said plunger, and a spring above said plunger.

4. A locking-device for doors comprising 100 a cylinder closed at its ends and provided with a longitudinal slot, a plunger vertically movable in said cylinder having means for locking into a door, a piston beneath said plunger serving to elevate the same, a spring 105 above said plunger serving to lower the same, a valve-chamber beneath said piston and having an air-inlet and an air-outlet, and a valve for opening and closing said inlet and outlet actuated by said plunger. 110

5. In a locking-device for doors, the combination with a structure having a door-opening and a door for closing said opening, of a cylinder forming the door-jamb, and having a valve-chamber arranged centrally 115 in its lower end and provided with an air-inlet and an air-outlet, a valve within said chamber having an axial valve-stem, a plunger within the cylinder having means for locking said door and having said valve-stem connected therewith, and a piston in said cylinder between said plunger and said valve through which said valve-stem extends. 120

6. In a locking-device for doors, the combination with a structure having a door-opening and a door for closing said opening, of a cylinder forming the door-jamb and having a valve-chamber arranged centrally in its lower end and provided with an air-inlet and 125 130

air-outlet, a valve within said chamber having an axial valve-stem, a plunger within the cylinder having means for locking said door and having said valve-stem connected therewith, and a coil-spring acting against the upper end of said plunger.

7. In a locking-device for sliding-doors, the combination with a structure having a door-opening and a door for closing said opening provided with hook-lock arms, of a cylinder forming the door-jamb, a reciprocating plunger within said cylinder and having hook lock-arms for interlocking engagement with the lock-arms of said door, air-controlled means for elevating said plunger, and means for holding said plunger elevated.
8. In a locking-device for sliding-doors, the combination with a structure having a door-opening and a door for closing said opening, of a cylinder forming the door-jamb, a reciprocating plunger within said cylinder having a series of teeth and means for locking said door when closed, power-controlled means for elevating said plunger, and a weighted detent-pawl adapted to engage one of said teeth when said door is open and to be disengaged therefrom when said door is closed.
9. In a locking-device for sliding-doors, the combination with a structure having a door-opening and a door for closing said opening, of a cylinder forming the door-jamb and having a longitudinal slot, a reciprocating plunger within said cylinder having a

lock-arm extending through the slot of said cylinder and adapted for locking engagement with said door and having also a vertical series of teeth, power-controlled means for elevating said plunger, a spring bearing against the upper end of said plunger, and a detent-pawl engaging the teeth of said plunger when the latter is elevated.

10. In a locking-device for sliding-doors, the combination with a structure having a door-opening and a door for closing said opening, of a cylinder forming the door-jamb, a reciprocating-element within said cylinder adapted for locking-engagement with said door, air-controlled means for actuating said reciprocating-element so as to move the same into position for unlocking said door, and means for holding said reciprocating-element in said last-mentioned position.

11. A locking-device for doors comprising a vertically-disposed cylinder, a reciprocating locking-plunger within said cylinder adapted to cause the door to be locked or unlocked, a power-actuated piston also within said cylinder beneath said plunger to elevate the latter, and means to lower said plunger.

In testimony whereof, I have affixed my signature in the presence of two subscribing witnesses.
